CLAIM

The ornamental design for remote control, as shown and described.

DESCRIPTION

FIG. 1 is a front view of the remote control according to the new design;

FIG. 2 is a left side view of the remote control;

FIG. 3 is a right side view of the remote control;

FIG. 4 is a back view of the remote control;

FIG. 5 is a front perspective view of the remote control

FIG. 6 is a top view of the remote control; and,

FIG. 7 is a bottom view of the remote control.

The broken lines in the Figures show portions of the remote control that form no part of the claimed design.
